Sharper Image 10 in. Lunar Drone with Camera Streaming by Kohl's. dated Dec. 22, 2017. found online [Oct. 25, 2018] https://www.kohls.com/product/prd-2978559/the-sharper-image-10-in-lunar-drone-with-camera-streaming.jsp?skuid=84227756&ci_mcc=ci&utm_campaign=ELECTRONICS&utm_medium=CSE&utm_source=bing&CID=shopping20&utm.*

Primary Examiner — Marissa J Cash

(74) Attorney, Agent, or Firm — Avyno Law P.C.

(57) **CLAIM**

I claim the ornamental design for a drone, as shown and described.

DESCRIPTION

FIG. 1 is a top perspective view of a drone.

FIG. 2 is a bottom perspective view of the drone of FIG. 1.

FIG. 3 is a side view of the drone of FIG. 1.

FIG. 4 is a side view of the drone of FIG. 1.

FIG. 5 is a side view of the drone of FIG. 1.

FIG. 6 is a side view of the drone of FIG. 1.

FIG. 7 is a top view of the drone of FIG. 1; and,

FIG. 8 is a bottom view of the drone of FIG. 1.

In the drawings, the broken lines depict portions of the drone that form no part of the claimed design.
